SEALING DEVICE FOR TUBULAR SHAFTING

Armais Arutunoff, Bartlesville, Okla.

Application December 6, 1951, Serial No. 260,177

3 Claims. (Cl. 255—28)

1 My invention consists in new and useful improvements in sealing means for extendable rotary shafting and more particularly shafting of the type used in connection with core drilling apparatus such as that illustrated and described in my co-pending application, Serial No. 121,579, filed October 15, 1949, now Patent No. 2,654,572.

In core drilling apparatus such as that shown in my said co-pending application, an electric motor-driven unit is suspended on a power cable and the drilling tool is carried at the lower end of a tubular shaft which also circulates fluid to the area being drilled. The unit is provided with an arrangement designed to break off a core from the rock being drilled, by utilizing the force of inertia of the upward moving mass of the drilling tool rather than by an excessive pull on the hoisting cable. This is accomplished by an arrangement of telescoping tubular shaft sections, the lower section of which carries the core bit with the upper sections being operatively connected to the power driving mechanism. In order to transmit the necessary torque from one shaft section to the other, the telescoping sections are slidably splined to each other and under normal conditions the clearances around the splines will permit the circulating liquid inside the shafting to leak past the splines which naturally results in the waste of the pressure liquid and in the rapid wear of the splined surfaces by the abrasives which are unavoidably carried in the circulating liquid.

It is the primary object of the present invention to provide a simple and effective means for the elimination of this leakage between two telescoping sections which are operatively connected either by splines or key arrangements.

Another object of the invention is to provide a sealing device which consists of an elongated tubular sleeve adapted to be installed in connection with telescoping shafting such as that shown in my said co-pending application, without the necessity of altering the latter structure.

With the above and other objects in view, which will appear as the description proceeds, my invention consists in the novel features herein set forth, illustrated in the accompanying drawings, and more particularly pointed out in the appended claims.

Referring to the drawings in which numerals of like character designate similar parts throughout the several views, Figures 1 and 2 are to be considered together.

Figure 1 represents a view in side elevation, partly broken away, of the upper portion of the

assembly which houses the circulating pump and speed reduction gearing of the drilling device shown in my co-pending application, Serial No. 121,579, while

5 Figure 2 is a longitudinal sectional view of the lower portion of said assembly, showing the connection of the extendable shaft to the core bit, and

Figure 3 is an enlarged longitudinal sectional view of the elongated tubular sealing sleeve used in connection with telescoping sections of the extendable shafting.

In the drawings, referring to Figure 1, 4 represents the cylindrical housing of the circulating pump and reduction gearing assembly, the housing being threaded at its upper end 5 for connection to an electric motor and bailer assembly, not shown in the present drawings but illustrated in my said co-pending application. A tubular shaft section 6 extends longitudinally through the housing 4 and is operatively connected to and driven by a reduction gearing assembly (not shown) in the upper portion of the housing, said shaft being concentrically supported in the housing by suitable bearings 7 which permit rotary movement of the shaft 6. The lower end of the shaft section 6 is splined as at 8 (Figure 2) for operative engagement with complementary splines in a collar 9 so that the latter rotates with the shaft 6.

10 A lower shaft section 10 is arranged coaxially with respect to the upper section 6 and is of slightly larger inside diameter to permit the telescoping of section 6 therein. This lower section 10 carries at its upper end a heavy annular collar 11 in threaded engagement with said shaft section as at 12. The collar 11 which will be referred to hereinafter as an anvil or knocker, is also provided in its bore with a series of splines adapted to mesh with the splines 8 on the upper

15 shaft section 6, whereby the rotation of shaft section 6 is transmitted to shaft section 10, even though the knocker and its attached shaft sections may travel axially relative to the shaft 6.

35

40

The lower end of the housing 4 is closed by a heavy cylindrical base 13, threaded into the housing as at 14 and provided with a longitudinal, coaxial bore 15 through which the lower end of the lower shaft section 10 protrudes for connection to the stem 16 of a drill bit (not shown). The upper extremity 17 of the base 13 serves as an annular abutment for the knocker 11 and upon relative movement of the two shaft sections, acts as a lower stop for the knocker, the collar 9 serving as an upper limiting stop for said knocker.

45 Since the base 13 is stationary in operation

and the knocker 11 often is rotating when it engages the abutment 17, the knocker preferably carries on its under side a loosely supported bearing race 18 which actually contacts the abutment 17 and minimizes the frictional resistance that otherwise would exist between the relatively rotating parts.

The foregoing structure is described in some detail in my said co-pending application but the above reference thereto is believed sufficient for the purposes of understanding the present invention. My improved sealing device consists of an elongated tubular sleeve 19 shown in detail in Figure 3, and its lower end is provided with an enlarged base 20 having a central bore 21 offset as at 22 to receive the end of the sleeve 19, the base 20 being preferably welded to the sleeve as at 23. The lower end of the base 20 is provided with a radial flange 24, which as shown in Figure 2 is adapted to serve as a retaining shoulder, cooperating with the threaded end 25 of the lower shaft section 10, when the latter is screwed into the coupling member of drill stem 16. An annular groove 26 surrounds the base 20 and is adapted to receive a suitable sealing ring 27 when the sleeve 19 and base 20 are inserted longitudinally in the shaft section 10. Thus, the lower end of the sleeve 19 is maintained in concentrically fixed relation with respect to the shaft section 10 with its upper portion extending into the lower end of upper shaft section 6 in sliding engagement therewith. A series of annular grooves 28 are provided at the upper end of the sleeve 19 to receive a corresponding series of sealing rings 29 for sealing the upper end of the sleeve with respect to the inner wall of shaft section 6. With this structure it will be seen that the bore of sleeve 19 forms a continuation of the fluid passageways provided in the tubular sections 6 and 10, to connect the source of circulating fluid with the hollow drill stem 16. Obviously the length of the sleeve 19 should be such that its upper sealing extremity maintains engagement with the inner shaft section 6 when the two telescoping sections are extended to the limit permitted by the stop collar or knocker 11.

In operation, the entire unit is lowered on a cable (not shown) into a well to drill a core and the weight of the bit, shaft section 10, and knocker 11, will cause the shaft section to be extended from the lower end of the housing 4 and base 13 with the knocker 11 resting on the abutment 17. When the bit approaches the bottom of the hole, the motor is started, but the advance of the bit naturally stops as the bit reaches the bottom. However, the operator continues to pay out the cable, allowing the balance of the unit to descend and during the course of this operation the shaft section 10 recedes into the housing 4 until the large collar 9 comes to rest on the knocker 11. The weight of the entire unit now is imposed on the bit. With the mass of the entire device urging the rotating bit downwardly, the cable slowly is paid out in order to drill the desired core and permit the core barrel of the bit to advance over the same, well fluid being circulated through the tubular shaft sections 6 and 10, all as described in my said co-pending application.

When the drilling of the core is completed, the core is at this point still connected at its base to the native formation so that it is necessary to break it loose in order to lift it to the surface for examination. In order to effect the detachment of the core, the operator reels in the cable with his hoist which is started slowly to avoid imposing

undue strain on the cable as it commences to lift the heavy mechanism in the bore hole. The core barrel, being securely anchored to the core by the core catcher, produces no substantial resistance to the initial upward movement of the device since the shaft section 10 simply is drawn out of the housing as the latter travels upwardly, the bit, shaft section 10, and knocker 11, in effect, being left behind. With the continuing upward movement of the mechanism, the shaft section 10 finally reaches the limit of its extension and the upward momentum of the heavy apparatus, now moving quite rapidly, causes the abutment 17 to strike the knocker 11 with an abrupt hammer blow and the transmission of this blow to the core breaks the latter loose from its moorings and carries it along to the surface with the unit. The motor is now halted.

During the course of this operation relative movement between the upper and lower shaft sections 10 and 6 is permitted but leakage of the circulating fluid from the interior of these shafts to the splined section where the two are telescopically joined, is prevented by the sealing of the upper end of sleeve 19 with respect to the inner wall of the shaft section 6, as at 29, and the sealing of the lower end of the sleeve with respect to the interior of the lower shaft section 10 as at 27.

The vacuum caused by member 6 withdrawing from the annulus between members 9 and 15 as the joint is extended, is relieved by the clearance passages inherent to a spline connection. The splines have a clearance between their outside dimensions on the shaft and the female member as also between the inside dimensions of the female part and the bottom of the spline groove on the shaft. No vacuum will be noticeable since fluid can fill or be displaced out of the space referred to at the time of withdrawal.

From the foregoing it is believed that my invention may be readily understood by those skilled in the art without further description, it being borne in mind that numerous changes may be made in the details of construction without departing from the spirit of the invention as set forth in the following claims. For example, while I have shown and described my improved sealing device as applied to the particular structure illustrated in my co-pending application No. 121,579, I do not intend to confine the invention to such use. Obviously this sealing sleeve may be employed with equal effect in connection with various forms of telescoping shaft sections employed for conducting a liquid or gaseous medium and designed for relative movement between the telescoping sections.

I claim:

1. In a core breaker for a rotary drilling device, comprising a housing, a rotary, fluid conducting, extendable, drilling shaft including an inner tubular driving part and an outer tubular driven part arranged in telescoping relation, means operatively connecting the two parts for imparting rotary motion from the inner to the outer part, said outer part being axially slidable through an aperture in the bottom of said housing and having means at its lower end for connecting a drilling tool, said inner part being rotatable in said housing but fixed against axial movement therein, a sealing device for said parts comprising an elongated sleeve fixed concentrically in the outer part in spaced relation to the inside wall thereof and secured to the lower end of the outer part, with its opposite end extending longitudinally in-

to the inner part in sliding relation thereto, means sealing the outside wall at opposite ends of said sleeve, with respect to the inside walls of respective telescoping parts, the bore of said sleeve forming a continuation of the tubular passage-way in said inner part, said sleeve having a length extending into the inner of said parts sufficient to maintain sealing engagement with the inner surface thereof when said parts are in fully extended position.

2. Apparatus as claimed in claim 1, wherein said sleeve is provided at its lower end with an enlarged annular base adapted to fit closely within the adjacent end of the outer driven part, said base having a radial flange for engagement between the end of said last-named part and the drill tool-connecting means, for rigidly securing the base of the sleeve in place in said driven part.

3. A sealing device for tubular sections arranged in telescoping relation, comprising an elongated sleeve slidably engaging the inside wall of the inner telescoping section and extending

coaxially from the latter into the outer section, in spaced relation to the inside wall thereof, the extended extremity of said sleeve being provided with an enlarged base adapted to fit closely within the adjacent end of said outer telescoping section, said base having an annular radial flange and means cooperating with said flange for fixing the base to the adjacent end of said outer section, means sealing said sleeve with respect to the inside wall of said outer section, and means sealing the opposite end of said sleeve with respect to the inside wall of said inner section.
